UNITED STATES PATENT OFFICE.

GABRIEL MARTINEZ, OF NEW YORK, N. Y.

CALCULATING-MACHINE.

1,194,760.

Specification of Letters Patent. Patented Aug. 15, 1916.

Application filed June 23, 1914. Serial No. 846,733.

To all whom it may concern:

Be it known that I, GABRIEL MARTINEZ, a citizen of the Republic of Mexico, residing in the borough of Manhattan, in the city of New York, county and State of New York, have invented certain new and useful Improvements in Calculating-Machines, of which the following is a specification.

The object of this invention is to provide an inexpensive portable calculating-machine. For this purpose a number of cup-shaped dial members are arranged in series and over the same are mounted rotatable counter-plates, each provided with spaces for exposing one of the rows of figures on the dial member beneath it, and with a recess for exposing one figure of a second row of figures, nine of which remain concealed at any time by the counter-plate. The fixed dials are disposed side by side in the same horizontal plane and have their faces individually inclined to said plane and the rotary counter-plates are disposed side by side in individually inclined positions on said inclined dials. These inclined counter-plates are so disposed relatively that the high part of the one plate is adjacent to the low part of the next. Each counter-plate is provided on its face with a series of upright posts near its periphery and with an elevated outwardly projecting finger. The inclined positions of the counter-plates permits the elevated outwardly extending finger of one plate to pass over and escape engagement with the posts of the adjacent counter-plate of the next lower order of numerals and causes such finger to engage a post of the adjacent counter-plate of the next higher order.

In the accompanying drawing, Figure 1 is a plan of a calculating-machine embodying the invention, Fig. 2 is a front-view, the cover being laid flat, Fig. 3 is a transverse section on line 3—3 of Fig. 1, and Figs. 4 and 5 are detail views of two of the cup-shaped dial members.

Similar reference characters indicate the same parts throughout the views.

The base 10 and its cover 11 may be of any suitable material, such as wood. On the base are arranged consecutively a plurality of cup-shaped dial members 21, 22, 23, 24, 25, 26 respectively. These members are located close together and, instead of being of uniform height over their entire circumference, are, on the contrary, inclined at

their upper edge, that is to say, the advancing side of each cup-shaped dial member, that is to say, the side toward and nearest the next cup-shaped member, is depressed. 60 This is clearly shown in Fig. 2. Counter-wheels 31, 32, 33, 34, 35, 36 are mounted, each respectively upon a standard or stud 12 rising from the base through the center of each dial member. Said counter-plates are 65 supported by said posts 12 and are provided with radial arms 14, which rest on the upper edges 15 of the dial members. The body of each counter-plate is of sufficient area to hide from view the inner row 16 of figures 70 of the dial member, while the radial arms form between themselves segmental spaces outside of the body of the plate, in which are exposed the figures of the outer row of figures 17 of the dial member. 75

Each of the arms 14 carries at its outer end an upwardly-projecting post 18, and one of said posts carries a radially-projecting finger 19, which finger projects far enough to engage once in each revolution of 80 the counter-plate with one of the posts of the next counter-plate of the series, and thereby turn the second counter-plate a distance of one space or figure on the dial member. The inclined position of the 85 counter-plates permits the laterally extended finger of one plate to escape the posts of the adjacent plate of the next lower order of numerals. An abutment 27 is arranged in front of each counter-plate and extends over 90 the same above the path of the posts 18.

For using the device, an operating-pin 20 is taken by the operator, who inserts it in that space between the arms of the counter-plate corresponding to the number of units, 95 etc., which he wishes to add. If he inserts the same, for instance, in the space in which appears the figure 3 in the dial member 21 and now moves the pin 20 while still engaged with the counter-plate, downward 100 until the pin strikes the abutment 27, he will have brought opposite the figure 3 of the inner series of figures 16, a recess 28 in the body of the counter-plate 31, thereby exposing the figure 3 of said inner series in 105 said recess, and indicating thereby that the machine has been operated to that extent. If the same operation be again carried out, recess 28 will be brought around so as to expose the figure 6 of the inner series 16 of 110 figures of the dial member. In case now five more units be added, which is accomplished

in the same manner, namely, by placing the pin 20 in the segmental space in which appears the figure 5 and bringing the pin around into engagement with the abutment 5 27, by such action the counter-plate will have been moved beyond the tens point, and the result will be that in passing the tens point the finger 19 of the counter-plate 31 will have engaged one of the posts 18 of the 10 second counter-plate 32 and moved the same a distance of one space over the second dial member. The same operation may be carried out with any of the dials. The dials indicate consecutively units, tens, hundreds, 15 thousands, tens of thousands, and hundreds of thousands. When the finger 19 of the second dial is at that side of its rotation adjacent the first counter-plate, the finger 19 does not engage any of the posts of said first 20 counter-plate on account of the inclination of the dial members, whereby the finger 19 is raised above the level of the posts, or, rather, the posts at that side of the dial member are depressed below the path of the 25 finger 19. The same applies to all the dials except the first, but for the sake of uniformity in construction, this dial member is also inclined. The finger 19 is omitted from the last counter-plate as there are no further counter-plates to be engaged. A spring-clip 37 and a stud 38 hold the manipulating-pin 20 in place on the base when the 30 same is not required for use.

The sum total of the operations on the 35 machine is always to be read from the figures found exposed in the recesses 28 of the successive counter-plates from left to right.

The machine described provides a comparatively inexpensive yet reliable portable 40 calculating-machine suitable for the use of all who have to do considerable amounts of figuring. It is convenient in operation, does not easily get out of order, and can be readily repaired.

45 One embodiment of the invention has been

described, but changes may be made therein without departing from the spirit of the invention as set forth in the following claims.

I claim:

1. In a calculating machine comprising 50 fixed dials disposed side by side in the same horizontal plane, the faces of said dials being individually inclined to said plane and the high part of one being adjacent to the low part of the next, rotary counter-plates 55 severally disposed side by side on said individually inclined dials, said counter-plates being severally provided with a series of upright posts one of which has an elevated outward finger, the relative inclined positions of said counter-plates permitting such elevated finger of one counter-plate to pass over the top of and escape contact with the posts of the adjacent counter-plate of the next lower order and causing such finger 60 to engage a post of the adjacent counter-plate of the next higher order, and stops for said counter-plates.

2. A calculating machine comprising a series of rotary disks severally disposed 70 side by side in individual inclined planes, the high part of one being adjacent to the low part of the next, said disks being provided near their peripheries each with a series of upright posts and with an elevated 75 outwardly extended finger, the relative inclined positions of said rotary disks permitting such elevated outwardly extending finger to pass over and escape the posts of the adjacent rotary disk of the next lower 80 order and to engage successively the several posts of the adjacent disk of the next higher order, and stops for said disks.

In testimony, that I claim the foregoing as my invention, I have signed my name in 85 presence of two subscribing witnesses.

GABRIEL MARTINEZ.
